CENTRIFUGAL PUMP

Harold A. Lockhart, Des Plaines, Ill., assignor to
 Bell & Gossett Company, Morton Grove, Ill., a
 corporation of Illinois

Application January 5, 1950, Serial No. 136,879

8 Claims. (Cl. 103—104)

1

My invention relates to centrifugal pumps of the radial flow type and more particularly to certain improvements therein which reduce manufacturing costs and facilitate assembly and disassembly.

The impeller assembly in pumps of the high velocity type, especially in the smaller sizes, is so constructed that the pump casing frequently must be composed of at least two parts which are bolted together to surround the assembly. Such an arrangement materially increases manufacturing costs which are important items in the highly competitive, small pump market.

It is therefore one object of my invention to devise a centrifugal pump in which the impeller assembly is arranged for endwise, axial mounting in operable relation to the volute of the pump casing that is cast in one piece.

A further object is to provide a pump of the character indicated in which the impeller assembly has a tight rim seal with the volute of the casing and a measure of looseness around the eye of the pump to prevent excessive return of the pumped liquid from the high to the low side of the pump externally of the outer shroud ring of the impeller.

These and further objects of the invention will be set forth in the following specification, reference being had to the accompanying drawing, and the novel means by which said objects are effectuated will be definitely pointed out in the claims.

The drawing is an elevation, partly in section, of the pump.

Referring to the drawing, the numeral 10 designates a centrifugal pump casing having an inlet 11 and an outlet 12 which are connected by the usual volute chamber 13. Coaxial with the chamber 13 is an impeller shaft 14 that is journaled in a bracket 15 attached to the casing 10 by studs 16. The shaft 14 may be driven in any approved manner, such as by a motor (not shown).

The hub 17 of an impeller 18 is keyed to the shaft 14 in symmetrical relation to the chamber 13 and a spring actuated seal assembly 19 encircles the shaft between the hub and an adjacent wall 20 forming part of the bracket 15. The impeller 18 includes inner shroud rings 21 and 22 whose inner peripheries are connected to the ends of the hub 17 and whose outer peripheries abut with their intervening portions curved as shown, outer shroud rings 23 and 24 curved to conform to the rings 21 and 22, and circumferentially spaced, Y-shaped blades 25 which are bridged between the shroud rings 21 and 23

2

and 22 and 24, respectively, throughout the radial extent of the rings 21 and 22 and between the shroud rings 23 and 24 outwardly of the rings 21 and 22.

5 The inner periphery of the ring 23 is extended to form an annular shell 26 which is coaxial with and spaced around the adjacent end of the shaft 14 to thereby form one eye 27 of the pump. Similarly, the inner periphery of the shroud ring 24 is extended in the opposite direction to form a like annular shell 28 that is spaced from the shaft 14, including the seal assembly 19, to form the other eye 29. The impeller is therefore of the double suction type which is self-balanced against end thrusts. As is well understood in the art, liquid entering through the inlet 11 divides around the chamber 13 and flows through the eyes 27 and 29, or low pressure side of the pump, into the plurality of passages included between 10 the shroud rings and blades where it is forced outwardly and discharged into the chamber 13 between the outer peripheries of the rings 23 and 24, or high pressure side of the pump.

15 Since the periphery of the impeller 18 must have free working clearance with reference to the inner boundary of the volute chamber 13, defined by the annular bores 30 and 31 which are axially spaced to provide an annular opening to the chamber, some of the liquid issuing from the high pressure side of the impeller would flow externally of the impeller directly to the low pressure side, thus lowering the efficiency of the pump. The invention is concerned with substantially preventing this action by means which also render the impeller assembly capable of being bodily inserted in and withdrawn from operating relation to the chamber 13.

20 A closure ring 32 includes an outer peripheral and annular flange 33 which has press fit relation to the bore 30 and an inner peripheral and annular flange 34 which surrounds the shell 26 and is slightly spaced therefrom, the intervening portion of the ring 32 being spaced from the shroud ring 23. A second closure ring 35, generally similar to the ring 32, is provided with outer and inner, annular flanges 36 and 37, respectively, the former having an easy fit relation with the bore 31 and the latter surrounding and being spaced from the shell 29. The fit of the flange 36 within the bore 31 may be of the order of ".003" to ".004".

25 The flanges 33 and 36 constitute the rim seals of the pump which prevent loss of liquid laterally between the impeller and bores 30 and 31 and the radially outward, pumping action of the ex-

ternal surfaces of the shroud rings 23 and 24 with respect to liquid between the closure and shroud rings combats to a substantial extent the tendency of the liquid to flow from the high to the low pressure side between the closure and shroud rings. This action is facilitated by the general similarity in conformation of the closure and shroud rings and their spacing from each other to define outwardly extending channels of shallow depth, all as shown in the drawing. Leakage losses are accordingly reduced to a minimum with a corresponding increase in efficiency.

The flange 36 rests on and may be secured to an annular flange 38 provided on one end of a frustoconical carrier 39 whose opposite end is similarly flanged at 40 and press fitted or secured to an annular shoulder 41 formed on the bracket 15. The portion of the carrier 39 between its flanges is provided with a plurality of circumferentially spaced apertures 42 through which 15 the liquid flows to the pump eye 29.

With the above arrangement, incoming liquid flows with equal facility to both eyes of the pump and since the diameter of the rim seal to the left of the impeller is not less than the impeller diameter, being in fact slightly greater in the design shown, it is possible to remove the nuts from the studs 16 and separate the bracket 15 from the casing, along with the shaft 14 and the associated assembly, including the impeller 12, 30 closure ring 35 and carrier 39. The casing 10 may therefore be cast in one piece and the complete pump is then characterized by the advantages set forth above.

I claim:

1. A centrifugal pump comprising a casing having a side opening and a volute chamber provided with an axial bore and including an annular opening connecting the chamber and bore, a member closing the side opening and having an annular shoulder, a shaft journaled in the member in coaxial relation to the bore, an impeller including peripheral outlets keyed to the shaft and having an outer shroud ring whose radially inward portion is extended to provide an annular shell surrounding and spaced from the shaft to define the axial eye of the pump, the peripheral outlets of the impeller being operably related to the annular opening, a closure ring spaced from the shroud ring and having annular outer and inner flanges, the outer flange fitting the bore to provide a rim seal for the impeller and the inner flange encircling the shell in spaced relation thereto, and a perforated, annular carrier supported on the shoulder and having support relation to the outer flange of the closure ring, the peripheral diameter of the outer flange being not less than that of the impeller.

2. A centrifugal pump comprising a casing having a side opening and a volute chamber provided with an axial bore and including an annular opening connecting the chamber and bore, a member closing the side opening and having an annular shoulder, a shaft journaled in the member in coaxial relation to the bore, an impeller including peripheral outlets keyed to the shaft and having spaced shroud rings whose radially inward portions are oppositely extended to provide annular shells surrounding and spaced from the shaft to thereby form a pair of axial 70 eyes, the peripheral outlets of the impeller being operably related to the annular opening, a closure ring spaced axially from each shroud ring and having annular outer and inner flanges, the outer flanges fitting the bore to provide rim seals

on opposite sides of the impeller and each inner flange encircling the shell of the adjacent shroud ring in spaced relation thereto, and a perforated, annular carrier supported on the shoulder and having support relation to the outer flange of the adjacent closure ring, the peripheral diameter of the last named flange being not less than that of the impeller.

3. A centrifugal pump comprising a casing 10 having a side opening and a volute chamber provided with an axial bore and including an annular opening connecting the chamber and bore, a member closing the side opening and having an annular shoulder, a shaft journaled in the member in coaxial relation to the bore, an impeller including peripheral outlets keyed to the shaft and having an outer shroud ring whose radially inward portion is spaced from the shaft to define the eye of the pump, the peripheral outlets of the impeller being operably related to the annular opening, a closure ring spaced from the shroud ring and having an annular outer flange, the outer flange fitting the bore to provide a rim seal for the impeller and the radially inward portion of the closure ring encircling the inward portion of the shroud ring in spaced relation thereto, and a perforated, annular carrier supported on the shoulder and having support relation to the outer flange of the closure ring, the peripheral diameter of the outer flange being not less than that of the impeller.

4. A centrifugal pump comprising a casing having a side opening and a volute chamber provided with an axial bore and including an annular opening connecting the chamber and bore, a member closing the side opening and having an annular shoulder, a shaft journaled in the member in coaxial relation to the bore, an impeller including peripheral outlets keyed to the shaft and having spaced shroud rings whose radially inward portions are spaced from the shaft to thereby form the eyes of the pump, the peripheral outlets of the impeller being operably related to the annular opening, a closure ring spaced axially from each shroud ring and having an annular outer flange, the outer flanges fitting the bore to provide rim seals on opposite sides of the impeller and the radially inward portion of each closure ring encircling the inward portion of the adjacent shroud ring in spaced relation thereto, and a perforated, annular carrier supported on the shoulder and having support relation to the outer flange of the adjacent closure ring, the peripheral diameter of the last named flange being not less than that of the impeller.

5. A centrifugal pump comprising a casing having a side opening and a volute chamber provided with an axial bore and including an annular opening connecting the chamber and bore, a member closing the side opening and having an annular shoulder, a shaft journaled in the member in coaxial relation to the bore, an impeller including peripheral outlets keyed to the shaft and having an outer shroud ring whose radially inward portion is spaced from the shaft to define the eye of the pump, the peripheral outlets of the impeller being operably related to the annular opening, a closure ring spaced from and generally conforming to the shape of the shroud ring to define therewith a shallow, annular channel whose outer end communicates with the annular opening, the closure ring having an annular outer flange fitting the bore to provide a rim seal for the impeller and the radially inward portion of the closure ring en-

circling the inward portion of the shroud ring in spaced relation thereto, and a perforated, annular carrier supported on the shoulder and having support relation to the outer flange of the closure ring, the peripheral diameter of the outer flange being not less than that of the impeller.

6. A centrifugal pump comprising a casing having a side opening and a volute chamber provided with an axial bore and including an annular opening connecting the chamber and bore, a member closing the side opening and having an annular shoulder, a shaft journaled in the member in coaxial relation to the bore, an impeller including peripheral outlets keyed to the shaft and having spaced shroud rings whose radially inward portions are spaced from the shaft to thereby form the eyes of the pump, the peripheral outlets of the impeller being operably related to the annular opening, a closure ring spaced axially from each shroud ring and having an annular outer flange, each closure ring generally conforming to the shape of the adjacent shroud ring and defining therewith a shallow, annular channel whose outer end communicates with the annular opening, the outer flanges fitting the bore to provide rim seals on opposite sides of the impeller and the radially inward portion of each closure ring encircling the inward portion of the adjacent shroud ring in spaced relation thereto, and a perforated, annular carrier supported on the shoulder and having support relation to the outer flange of the adjacent closure ring, the peripheral diameter of the last named flange being not less than that of the impeller.

7. A centrifugal pump comprising a casing having a side opening and a volute chamber provided with an axial bore and including an annular opening connecting the chamber and bore, a member closing the side opening and having shoulder means, a shaft extending through the member in coaxial relation to the bore, an impeller including peripheral outlets keyed to the shaft and having an outer shroud ring whose radially inward portion is spaced from the shaft to define the eye of the pump, the peripheral outlets of the impeller being operably related to the annular opening, a closure ring spaced from the shroud ring and having an annular outer flange, the outer flange fitting the bore to provide a rim seal for the impeller and the radially inward

portion of the closure ring encircling the inward portion of the shroud ring in spaced relation thereto, and carrier means supported on the shoulder means and having support relation to the outer flange of the closure ring, the carrier means being arranged to provide for fluid flow to the eye and the peripheral diameter of the outer flange being not less than that of the impeller.

8. A centrifugal pump comprising a casing having a side opening and a volute chamber provided with an axial bore and including an annular opening connecting the chamber and bore, a member closing the side opening and having shoulder means, a shaft extending through the member in coaxial relation to the bore, an impeller including peripheral outlets keyed to the shaft and having spaced shroud rings whose radially inward portions are spaced from the shaft to thereby form the eyes of the pump, the peripheral outlets of the impeller being operably related to the annular opening, a closure ring spaced axially from each shroud ring and having an annular outer flange, the outer flanges fitting the bore to provide rim seals on opposite sides of the impeller and the radially inward portion of each closure ring encircling the inward portion of the adjacent shroud ring in spaced relation, and carrier means supported on the shoulder means and having support relation to the outer flange of the adjacent closure ring, the carrier means being arranged to provide for fluid flow to the adjacent eye and the peripheral diameter of the last named flange being not less than that of the impeller.
